A. E. CARLBERG

WRENCH

Filed June 10, 1924

UNITED STATES PATENT OFFICE.

AUGUST EDWIN CARLBERG, OF WORCESTER, MASSACHUSETTS, ASSIGNOR TO WALDEN-WORCESTER, INC., OF WORCESTER, MASSACHUSETTS, A CORPORATION OF MASSACHUSETTS.

WRENCH.

Application filed June 10, 1924. Serial No. 719,060.

This invention relates to wrenches and is particularly concerned with wrenches of the type in which the socket or like nut engaging member is pivotally associated with a projection substantially at right angles to the shank.

This invention is in the nature of an improvement on the wrench described in my copending application, Serial No. 581,010, filed January 23, 1922, Patent No. 1,542,336, granted June 16, 1925.

It is the object of the present invention to provide a wrench in which the angular relation between the shank and the nut engaging portion may be readily changed to adapt the wrench for use in restricted places and under difficult conditions and which will be of a nature suited for quantity manufacturing and economical production.

Another object of the invention is to provide a wrench of the type described in which the sockets are removably retained upon the shank so as to be readily interchangeable to provide different size nut engaging portions.

A further object of the invention is to provide a wrench socket or adapter for use with shanks of the type described, having a cylindrical hole thru the body of the socket or adapter, which fits upon said shank, with a spring pressed ball or plunger projecting into said hole and adapted to engage the shank in place, and to provide a novel method for inserting the spring pressed ball in the socket member or adapter and for securing the ball in place.

A good understanding of the invention may be had from the following description of several specific forms of embodiment thereof, reference being had to the accompanying drawings, in which:

Figure 1 is an elevation of the single ended type of wrench embodying my improved construction with the adapter and wrench socket thereof shown in cross section to show the relative position of the parts.

Figure 2 is an elevation of a double ended type of wrench with one of the nut engaging portions thereof in cross section to illustrate the relative position of the parts.

Figure 3 is a fragmentary view of a modified form of the wrench.

Figure 4 is a part sectional view of a

modified manner of detachably connecting the socket to the shank. 55

Figure 5 serves to illustrate one method of mounting the retaining ball in the wrench head.

In the embodiment illustrated in Figure 1, the shank H has its end portion 5 bent at substantially right angles to the axis thereof, to receive the wrench member, said bent portion being provided with groove 7. 60

The wrench head or adapter 9 is provided with a bore 10, adapted to fit upon the shank portion 5, and with a further bore 12, substantially at right angles to the bore 10. For the purpose of securing the head or adapter 9 on the shank portion 5, a ball 14 is preferably pressed into the groove 7 by such means as spring 16. Thus it will be seen that the head 9 may be pulled endwise from the portion 5, or inserted thereon with comparatively little effort as the curved bottom of groove 7 pushes the ball 14 inwardly against the spring 16, however, the ball 14 serves to retain the wrench member securely in place upon the shank and prevents loss or accidental slipping of the wrench member from the shank. Portion 5 is shown as round and head 9 may pivot thereupon, allowing the shank H to assume any desired angular relation to the nut engaging portion. Manifestly, portion 5 may be square or polygon shape if it is desired that the head assume definite predetermined relationship to the shank. 70 75 80

The head or adapter 9 is provided with a projection 20, of square cross section, adapted for the engagement with a plurality of socket members 24, having the nut opening or engaging recesses 26 of different sizes formed therein. Projection 20 is also provided with a spring-pressed frictional retaining ball 14^a, for detachably holding socket members 24 in place. One size of shank H and head or adapter 9 may thus serve for the manipulation of a complete series of varying sized standard socket members 24, which may be engaged with the projection 20 by the simple operation of pushing them into place or of pulling them therefrom. 85 90

In the herein disclosed invention, it is my purpose to especially provide for the easy insertion and retention of the ball mem- 100 105

bers 14, at approximately the midpoint of the shank receiving hole of the socket. This, I accomplish, thru the means of the hole 12 which is provided thru the wall of the bore 10 at a point approximately diametrically opposite to the position of the ball 14 and the cavity in which it is retained.

Figure 2 shows a double ended socket 40 with a bore 10 therethru for fitting upon the turned ends 5 of the double ended shank H². In this embodiment the hole 12 is provided in one of the socket members, thru which the hole 17 may be drilled into the other socket member and the spring 16 and ball 14 inserted and secured therein.

Figure 3 illustrates a shank H³ with a pin 5^a projecting at right angles therefrom and a single socket 32 adapted to be secured directly upon the shank 5^a and provided with a spring pressed ball 14 for projecting into the groove 7 and with a hole 12 in the bore 10 opposite the ball whereby the ball can be easily inserted and retained in place.

Figure 4 shows a further means for detachably securing the sockets upon the right angular portion of the shank. In this embodiment, the ball 14 is secured in a hole 17^a in the shank portion 5 and is pressed outward by the spring 16 into the groove 7^a in the socket member 24^a.

Figure 5 illustrates one of the steps in the method of securing the retaining ball in the socket member. In inserting and securing the ball in place the hole 12 is first drilled into the approximate midpoint of the bore 10 and the drill is then projected thru the hole 12 to drill the hole 17 in the opposite wall of the bore 10; the spring 16 and the ball 14 are then inserted in the hole 17 and the edges of the hole 17 bent inward by means of a punch or the like 35 inserted thru the hole 12 to form the prongs 30 to hold the ball in place. To permit dislodging of the ball 14 in case it becomes stuck in retracted position in the hole 17 an aperture 36 may be provided as illustrated thru which a small punch or nail may be inserted for dislodging the ball 14 or if necessary to drive the ball out of the hole 17.

It is to be noted that in the embodiments of Figures 2, 3, and 5, the hole 12 is inside the socket so that the outward appearance of the wrench is not marred or changed by this method of securing the ball in place and in Figure 1, the countersunk upper portion of the hole 12 fits in with the general contour of the wrench so that the hole is scarcely noticeable.

I have, therefore, provided a ready means

for detachably and pivotally securing the wrench or socket members on the right angular projections from the shank which will not detract from or mar the appearance of the wrench and which can be easily and economically applied to the wrench.

Various modifications and changes may be made in the embodiments of the invention described and parts of the devices may be used without others without departing from the spirit of the invention or the scope of the appended claims.

I claim:

1. In a wrench combination, a shank, the entire shank being straight, said shank having a projection extending at right angles therefrom, a wrench socket having a hole therein at substantially right angles to the axis of the nut engaging portion thereof, said hole fitting upon said projection, one of said interfitting members being provided with an annular groove, and a spring-pressed ball in the other of said members projecting into said groove, to permit rotation of said socket on said projection but restrain removal of said socket from said projection.

2. In a socket wrench, a head member, provided with axially arranged work engaging sockets, said head member having a shank engaging recess having its axis at substantially right angles to the axis of the aforesaid socket, said head having an axial bore therein extending inwardly from one of said sockets to the opposite side of said recess and a spring pressed latch means projecting into said recess from the bore in said opposite side to engage and frictionally retain a shank inserted therein.

3. In a wrench socket, a nut-engaging portion having a shank-receiving bore at right angles to the axis thereof, and a hole inside said nut-engaging portion, extending thru the wall of said bore, and a spring-pressed locking means projecting into said bore opposite said hole.

4. An adapter for socket wrenches comprising a body portion, a socket engaging member projecting therefrom, means in said socket engaging member for frictionally retaining a wrench socket thereon, the said body portion having a bore at substantially right angles to said socket engaging member adapted to detachably fit upon the end of a wrench shank and means in said bore for frictionally retaining said adapter on a wrench shank.

In testimony whereof I have affixed my signature to this specification.

AUGUST EDWIN CARLBERG.
